UNITED STATES PATENT OFFICE.

HORACE W. ANDREWS, OF PORTLAND, OREGON.

DESIGN FOR A MOTOR-CHAIR.

43,077.

Specification for Design.

Patented Oct. 1, 1912.

Application filed August 4, 1911. Serial No. 642,417. Term of patent 7 years.

To all whom it may concern:

Be it known that I, HORACE W. ANDREWS, a citizen of the United States, residing at Portland, in the county of Multnomah and State of Oregon, have invented a new, original, and ornamental Design for Motor-Chairs, of which the following is a specification, reference being had to the accompanying drawing, forming part thereof.

The figure is a perspective view of a motor chair, showing my new design.

I claim:

The ornamental design for a motor chair, as shown.

HORACE W. ANDREWS.

Witnesses:

FANCHER NICOLL,
THOMAS M. FORD.
